Primary Examiner — Clare E Heflin(74) *Attorney, Agent, or Firm* — Cooper & Dunham, LLP(57) **CLAIM**

The ornamental design for a light projector, as shown and described.

DESCRIPTION

FIG. 1 is a front perspective view of a light projector in accordance with the present design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown on the drawings depict portions of the light projector that form no part of the claimed design.
